DIAPER

Virginia Blake, Miami, Fla.

Application October 1, 1949; Serial No. 119,167

1 Claim. (Cl. 128—287)

1. This invention relates to a diaper structure. The chief object of the present invention is to provide in a diaper a moisture repellant, or water blocking, sheet of flexible material which can be removed to permit boiling, washing and ironing of the other portions of said diaper and wherein the blocking sheet in use at all times is fully masked or covered so that in that diaper use this sheet cannot have contact with the infant's skin.

The chief feature of the present invention resides in forming a pocket in a diaper which pocket is adapted to receive a water blocking or moisture repelling sheet, and which sheet is fully concealed so that when the diaper structure is mounted for use no part of said blocking sheet is exposed for contact with the skin of the infant.

The fact that the blocking sheet is both removable and covered provides that any suitable blocking sheet material may be utilized regardless of whether it upon skin surface contact would cause sores, etc., or whether it can be boiled, washed or ironed without undue deterioration, etc.

The present invention accordingly permits a single blocking sheet to be interchangeably utilized in a plurality of diapers. This permits a set of diapers to be sold as a unit with but one blocking sheet thereby reducing the unit cost per diaper.

Other objects and features of the invention will be set forth more fully hereinafter.

The full nature of the invention will be understood from the accompanying drawings and the following description and claim:

In the drawings

Fig. 1 is a plan view of one embodiment of the invention looking at the inside or absorbing surface side thereof.

Fig. 2 is a sectional view of said diaper structure.

Fig. 3 is a plan view of a second embodiment of the invention.

Fig. 4 is a sectional view thereof.

Fig. 5 is a plan view of a third embodiment of the invention.

Fig. 6 is a sectional view thereof.

Fig. 7 is a plan view with successive portions turned back and of a further form of the invention.

Reference is first had to Figs. 1 and 2 of the drawings wherein 10 indicates the outside sheet or cover fabric or body that can be of any suitable material determinable by the purchaser's primary desire for ornamentation or quality

and/or color and/or decoration which may take the form of notion type edgings well known in the infant garment trade.

11 generally indicates one or more layers of water absorbing sheet material. If of more than one layer, they may be of dissimilar material and in some instances may comprise a pad-like formation. This portion of the garment broadly is termed the pad portion because it is of absorbing or blotting type. The layer that is outermost preferably is that known as "bird's-eye" diaper cloth or equivalent material.

12 indicates an intermediate water repellant, moisture blocking sheet material that prevents moisture in the inner sheet or pad 11 from passing to and wetting the outer sheet aforesaid.

The foregoing broad description applies to all forms of the invention herein disclosed as well as many others patented or otherwise which seek to displace the concurrent use of ordinary diapers with a pair of so-called rubber pants, such conventional usage having many present well-known objections.

Again referring to Figs. 1 and 2, the body portion 10 comprises two layers 10^a and 10^b peripherally secured together at 10^c as by sewing. It is generally of hourglass form having reentrant central portion 13 and band forming end portions 14 and 15. The latter may have included therein elastic tape 16. The aforesaid body may mount suitable connectors as complementary snap fasteners 17 and 18.

Superposed upon and suitably secured to body 10 as by sewing 19 along three sides is the pad portion 11 aforesaid comprised of one or more layers of absorbing material such as "bird's-eye" diaper cloth. All layers preferably are peripherally sewed together. Herein end 11^a is not fixed to the body 10 so that a pocket is formed by the pad and body.

The pad 11 is also of hourglass form but herein is not as long as body 10 nor as wide at the band portion 8. Herein it is as wide at the reentrant central portions 13.

45 The waterproof or blocking sheet 12 of flexible plastic, rubber, etc., has an outline similar to but slightly smaller widthwise as the pad 11 and somewhat shorter than the length of said pad. Hence it is readily insertible into and removable from the pocket formed as aforesaid and is automatically locked in place by virtue of its hourglass form and disposition in an hourglass outlined pocket.

No special skill is required for proper insertion 55 because unless it is properly located it will form

a crease or creases readily evident through the pad because the latter then will not lie flat. When the diaper is soiled or wet, the soil or moisture does not pass from the pad to the body. The blocking sheet can be interchangeably utilized in any number of diapers unless soiled. Consequently, a set of three or four diapers (less waterproof sheets 12) and one waterproof sheet 12—a set—can be used for a half day or a day's travel or two or more sets can be so used.

Reference will now be had to Figs. 3 and 4 wherein a somewhat similar form of diaper is illustrated. Numerals of the one hundred series designate parts similar or identical to the parts designated by the comparable primary numerals in Figs. 1 and 2.

This form is characterized by the pad having a plurality of layers of absorbing material, the innermost of which is sewed about its entire peripheral edge to the body portion 110. The exposed and supplementary other layers of the pad 111 are secured along their longitudinal reentrant portion including edges to the body. This leaves the band or crosswise ends open forming a longitudinally disposed hourglass form of pocket.

In this pocket, open at opposite ends, there may be inserted from either end and removed from either end an hourglass outlined blocking sheet 112 of lesser length and width as said pad.

Both of these forms provide diaper structures devoid of any fastening elements except such as are necessary, such as safety pins, snap fasteners, etc., to secure the band ends together to mount the garment upon the body of the infant.

Reference will now be had to Figs. 5 and 6 wherein a further modified form of the invention is illustrated numerals of the two hundred series herein indicate parts identical or similar to those in Figs. 1 and 2 and Figs. 3 and 4 designated by the corresponding primary numerals or the one hundred series numerals respectively.

Herein the pad-like pocket of the Figs. 3 and 4 form is retained but instead of having the pad structure 211 permanently attached to the body 210 it is detachably secured thereto as by snap fasteners 221 and 222, the complementary fastener portions being carried by the body and pad respectively reenforced by tapes 225. These fasteners are disposed at the corners of the pad and are concealed or padded as shown so that no part thereof or the blocking sheet 212 can touch the skin of the infant. If desired herein, the pad 211 and sheet 212 each may have, as well as the pocket, a rectangular outline as illustrated or the hourglass outline if desired.

Whenever it is desired, as in the preceding form, to have three separate elements and not utilize the hourglass outline to prevent longitudinal displacement of the blocking sheets, the invention may partake of type illustrated in Fig. 7.

In this figure numerals of the three hundred series are used to designate parts similar or like parts designated by the primary numerals or the one series or the two hundred series in Figs. 1 and 2, Figs. 3 and 4, or Figs. 5 and 6, respectively.

Herein the blocking sheet 312 again is smaller in outline than the absorbing pad 311. Herein each, at its four corners, is detachably connect-

ed to the body 310 as by snap fasteners 321—322 and 323—324 carried by pad and body and sheet and body respectively. As illustrated all fasteners and sheet 312 are covered by the pad so that no part of the former can contact the skin of the infant.

This form of the invention, as well as that shown in Figs. 5 and 6 permits detachment of the pad from the body and also separation of the sheet from the structure so that in both instances the pad only need be laundered when wet or soiled. Here again only one blocking sheet is required for a plurality of diaper units as in Figs. 1 to 4 and here also as in the Figs. 5 and 6 forms there may be sold but one body and one sheet for a multiplicity of pads.

This also permits the manufacturer to standardize, in these two latter forms, upon a single type pad structure, a single type sheet structure and an infinite number of body styles. Thus the mother can have one or two play bodies, one formal body and one highly ornamental body for the most formal occasions, all of which, however, can be interchangeably used with a single sheet and a plurality of identical pads.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claim.

The invention claimed is:

In a multiple piece diaper structure, a body portion, a pocket for a blocking sheet open at one end and secured along both sides and its other end to said portion, both sides of said pocket having re-entrant portions formed therein centrally of the ends thereof whereby said pocket is substantially of hourglass configuration, and a blocking sheet of water repellent material for said pocket, said blocking sheet having an area substantially that of but slightly less than the area of said pocket, the sides of said blocking sheet having re-entrant portions formed therein centrally of the ends of said sheet and corresponding with the re-entrant portions of said pocket whereby said blocking sheet may be removably positioned in interfitting engagement within said pocket.
